C. G. HAWLEY

STEAM BOILER

Filed Sept. 24, 1921

UNITED STATES PATENT OFFICE.

CHARLES GILBERT HAWLEY, OF CHICAGO, ILLINOIS.

STEAM BOILER.

Application filed September 24, 1921. Serial No. 503,064.

My invention relates to improvements in and for steam boilers of the kinds mainly used in the larger power houses and stations.

The object of my invention is to provide a steam boiler of high capacity and efficiency; and of a form and construction that shall particularly fit it for use in the larger sizes. My special purpose is to provide a boiler that may be safely and economically operated at the highest ratings and yet be of low original cost and adapted for maintenance at little expense.

To these ends my invention comprises a plurality of banks of vertical water tubes and the upper and lower drums belonging to them, in combination with a plurality of water circulating and steaming walls or thermic siphons which are connected with said drums to enforce circulation therein, and all such elements being connected and placed in cross-communication by cross-headers respectively at the ends of said upper and lower drums.

The invention also comprises other novel constructions and combinations hereinafter detailed.

My invention will be readily understood on reference to the accompanying drawings, in which Fig. 1 is a vertical, longitudinal section of a steam boiler embodying my invention, the section being taken substantially on the line 1—1 of the next figure; Fig. 2 is a top view of the boiler, partly in horizontal section on the line 2—2 of Fig. 1; Fig. 3 is an elevation of the upper part of the boiler front, partly in cross-section, as required to show the interiors of the top drums and the manner in which the hollow water-walls communicate therewith; Fig. 4 is a detail view showing how the intermediate water-walls are joined to the bottom cross header; Fig. 5 illustrates a modified form which may be adopted for the front ends of the upper drums of the boiler; Figs. 6 and 7 are horizontal sectional details of the water-wall, enlarged, on respective lines 6 and 7 of Fig. 1; and Fig. 8 is a sectional detail on the line 8 of Fig. 1.

The top of such a boiler may comprise any required number of cylindrical drums. Usually these are of two sizes or kinds; namely, a main drum or drums 2, of the larger size; and a secondary drum or drums, 3, of the smaller size. The lower drums, 4, of the boiler preferably correspond, in size, to the main drums, 2; but, as shown, they are only

about half as long and are positioned beneath the rear half of the upper drums. By preference all of the drums are large enough to freely admit a workman for purposes of inspection and work upon the interior of the boiler.

At the back end, all of the lower drums are cross connected by a fully staybolted cross-header, 5. Preferably there is a like header at each end of the upper drums. Theoretically such a header if placed at either front or back ends of the top drums would serve all necessary cross communication purposes; but practically, and for the sake of both cross communication and structural unity and integrity, the use of two top headers is recommended. The forward top header is marked 6, in the drawings; and the rear top header is marked 7. Throughout, the drums and headers are stayed by extra heavy bolts 8, as shown in Figs. 1 and 2. In addition all flat surfaces of the headers are stayed by properly spaced smaller staybolts. For the sake of clearness, the latter have been omitted from the drawing. The necessary man holes 9, and their covers 9', are provided in the outer sides of the headers 5, 6 and 7 and allow access to the interiors of the respective drums.

The parts marked 10 are banks of water tubes, of large number and extensive heating surface, which join each bottom drum with the main drum above it.

The part 11 is a feed water pipe leading into the back header, 5. The part 12 is a blow-off pipe which leads from the bottom of the header 5. The part 12' is an added blow-off connection leading from the bottom of the drum 4, at a point near its forward end. Preferably a blow-off, 12', is provided for each bottom drum 4.

The boiler as a whole is enclosed by the walls or setting 13. A bridge-wall 14 crosses the enclosed fire chamber directly ahead of the bottom drums, 4. The parts 15 are cross baffles among the banks of tubes 10, and form a tortuous gas passage which leads to the outlet or breeching 16.

As will be apparent, the top headers 6 and 7 rest upon the setting 13, or are suspended thereabove and constitute ideal anchorages for the assembled boiler.

The space 17 forward of the bridge wall is the fire chamber proper and usually contains a fuel grate 18. In this case an automatic chain grate is shown, with its characteristic arch 18'. The fire chamber extends from the

grate 18 to the underside of the top drums. The roof of the fire chamber as a whole is completed by properly shaped key brick 19, and slanting brick 20, wh ch close the spaces 5 between the drums and setting, as best shown in Fig. 3.

The fire chamber proper, 17, is occupied by the longitudinally positioned, transversely spaced, vertical water-walls, 21. One such 10 water-wall is provided for each top drum, 2, and one for each top drum 3. As indicated, the drums 3 are smaller than the drums 2, and nest between them and above the top of adjacent banks of tubes 10. The 15 use of the smaller drums, 3, admits of the employment of wide banks of tubes 10 and yet obviates the difficulty which would be presented if such widely spaced large drums were used and wide openings left to be 20 closed by brick-work between the large drums. But more important is the fact that by this construction or combination of large and small drums (reaching from header 6 to header 7) I make it possible to employ a 25 fully adequate number of water steaming and circulating walls, 21, within a fire chamber, 17, of normal width.

Each hollow water-wall is formed of boiler plate with spaced apart sides that are 30 joined by properly spaced stay bolts 21'. The upright ends 21^x and 21^y of the water wall are formed by closing together the edges of the boiler plate material and welding the edges as clearly shown in Figs. 6 35 and 7. At the top, the edges of the water wall merge with or are joined to the bottom of the respective top drum, and therefore, the whole top of the water wall or passage opens directly into the drum. The opening 40 itself has the form of a long, narrow slot, usually about half as long as the drum itself, as clearly indicated by the reference numeral 22, in Figs. 2 and 3. Such is the outlet opening of the water wall. The only inlet 45 opening of the water wall is found at the bottom rear corner thereof, and is there marked by an extended tubular portion or neck 21^z. In the case of the walls, 21, which depend from the main drums, 2, this intake neck is directly and tightly jointed to the 50 head, 4', of the corresponding bottom drum 4. In the case of the intermediate water walls, namely, those which depend from the smaller or secondary drums, 3, the neck portion, 21^z, is protracted or elongated and becomes a large pipe, 23, that extends back to, 55 and opens into, the bottom header 5. Each water wall has a slanting bottom, 21^y, the cross-sectional form of which is shown in 60 Fig. 8. The bottom of the water wall may have any preferred inclination downwardly and backwardly, but a very good arrangement is shown in full lines in Fig. 1 wherein the bottom extends upwardly toward the front from the drum 4 and terminates in a

blow-off neck 21^x. The necks, 21^x preferably penetrate the front wall of the boiler setting and are tightly capped or closed at that point. The blow-off connection which contains a blow-off valve (not shown) 70 appears at 26 (Fig. 1).

A steam outlet, 27, may be provided for each of the large drums, 2, or any other suitable outlet arrangement may be employed. The parts 28 are spaced hand-holes, which 75 I provide in the tops of the drums 2 and 3. When the boiler is to be cleaned internally, these hand-holes are opened; and through them, a workman standing upon the top of the boiler inserts and uses the necessary 80 cleaning tools; obviating the necessity of entering the drums for that purpose. By means of ordinary power tools operated by flexible shafts, all of the water tubes and 85 all of the interior surfaces of the water walls 90 may be reached through the hand-holes 28.

As will be apparent, this boiler may comprise a single large drum, 2, and two small drums, 3, with the accompanying water walls, tubes, bottom drum and cross header. 95 Or the boiler may be typified by two large top drums and one intermediate drum 3. And in brief, any desired number of the elemental units may be assembled within a single boiler setting, the number thereof depending upon the steaming capacity which is desired or required. The exemplary boiler herein shown, is characterized by three drums 2 in association with two small drums, 3, three bottom drums, 4, three banks of 100 tubes and five water-walls.

In operation the flames from the fuel on the grate 18, being afforded a free upward passage between the several water-walls, rise to full propagation and maturity therein, and thus impart a maximum of radiant heat to all of the surfaces of said walls. If desired, different arrangements of fire brick arches may be employed between or among the vertical water walls for the purpose of increasing the flame travel between the grate and the first point of impact with the banks of water tubes. Upon reaching the upper part of the fire chamber, the flames and gases encounter the roof, composed mainly of the drums 2 and 3, and thence pass among the tubes. From that point the flow of gases follows the tortuous course determined by the baffles, 15, and the heat of the non-flaming gases is effectively transferred to the water tubes before the gases escape at the outlet 16.

The boiler is filled with water to about half the height of the upper drums, 2, as 125 well shown in Figs. 1 and 3. The highest temperatures of the fire are imparted to the water within the substantially triangular or fan-shaped water walls, 21. Therein much steam is generated; and the columns of 130 water therein being much lighter than the

corresponding columns in the cooler water tubes, a natural and at the same time extremely vigorous circulation is set up, the water descending through the tubes 10 from the drums 2 into the bottom drum 4 and thence rising through the intake necks 21² into the water walls and rising and expanding rapidly therein returns to the top drum. The aggregate area of the tubes exceeds that of the water-wall necks and hence the downward movement of water through the tubes 10 is never so rapid as to prevent the free rise of all steam generated therein. Obviously, the wide open top of each water wall 15 is so many times larger than the intake neck that it affords a free outlet for the water and steam. And at the top the steam finds ample surface for its free and quiet disengagement from the water. Therefore there 20 is neither a suppression of steam disengagement nor a tendency to prime the steam at the boiler outlet.

As indicated, I prefer that the feed water shall enter the bottom drums 4 and sink to 25 the bottom thereof, and there precipitate most of the impurities or solids, thence to be occasionally discharged through the connections 12 and 12'.

To prevent any objectionable disturbance 30 of accumulations of mud on bottom of drums, 4, I prefer to employ baffle plates, 4'', therein, as indicated in Fig. 1. These plates, one in each drum 4, receive the downward moving streams from the tubes 10 and 35 to considerable extent prevent their penetration to the bottom of the drums, and therefore insure a measure of quiet in a body of cooler water in the bottoms thereof. In this manner the fed water is prevented from immediately encountering the hottest surfaces 40 of the boiler, the temperature being first raised by admixture with the hotter water from the tubes.

Various modifications of the structure 45 herein shown and described will suggest themselves to one who is skilled in the art and therefore I do not limit or restrict my invention thereto but rely upon the following claims to define the full scope of the 50 invention for which I seek a patent.

Having thus described my invention, I claim as new and desire to secure by Letters Patent:

1. A steam boiler composed of boiler units 55 placed side by side, each said unit comprising a long upper drum, a short lower drum, a bank of water tubes joining said drums, and a vertical water steaming and circulating wall forward of the lower drum and joining said drums, in combination with cross-communication headers respectively in the planes of and joining the upper drums and the lower drums.

2. A steam boiler composed of boiler units 60 placed side by side, each said unit compris-

ing a long upper drum, a short lower drum, a bank of water tubes joining said drums, and a vertical water steaming and circulating wall forward of the lower drum and joining said drums, in combination with cross-communication headers respectively in the planes of and joining the upper drums and the lower drums, and a suitable setting enclosing said units and providing a fire chamber that encloses said walls. 70

3. A steam boiler composed of boiler units placed side by side, each said unit comprising a long roof forming upper drum, a short lower drum, a bank of water tubes joining said drums, and a vertical water steaming and circulating wall forward of the lower drum and joining said drums, in combination with cross-communication headers respectively joining the upper drums and the lower drums, and a secondary roof forming drum alongside said upper drums and in header communication therewith. 80

4. A steam boiler composed of boiler units placed side by side, each said unit comprising a long upper drum, a short lower drum, a bank of water tubes joining said drums, and a vertical water steaming and circulating wall forward of the lower drum and joining said drums, in combination with cross-communication headers respectively joining the upper drums and the lower drums, a secondary drum alongside said upper drums and in header communication therewith, and another water wall communicating with each secondary drum and connected with the lower cross header. 90

5. A steam boiler composed of a long upper drum, in combination with a short lower drum, a bank of water tubes joining said drums, a vertical water steaming and circulating wall forward of the lower drum and joining said drums, a roof-forming secondary drum alongside said upper drum, a water steaming and circulating wall depending from said secondary drum, and means connecting the lower part of the last mentioned water wall to said lower drum. 100

6. A steam boiler composed of a long upper drum, in combination with a short lower drum, a bank of water tubes joining said drums, a vertical water steaming and circulating wall forward of the lower drum and joining said drums, roof-forming secondary drums, one on each side of said top drum, a water steaming and circulating wall depending from each said roof-forming drum, a cross-header upon said lower drum, and means connecting both last named water walls with said cross-header, whereby all of the water steaming and circulating walls are placed in communication with said lower drum. 110

7. A steam boiler composed of a large top drum between two smaller drums, in combination with a cross-communication 120

header joining said drums, a substantially triangular water-steaming-and-circulating wall depending from each said drum, each said wall presenting an intake neck and a blow-off neck, a bank of water tubes depending from one of said top drums, a short bottom drum which receives said tubes and the intake neck of the water wall belonging

to the large top drum and a bottom header at the end of said bottom drum and which cross connects the same to the intake necks of the other water walls. ¹⁰

In testimony whereof, I have hereunto set my hand this 22nd day of September, 1921.

CHARLES GILBERT HAWLEY.
